UNITED STATES PATENT OFFICE

160,058

LOVE SEAT

Salvatore Bevelacqua, Westport, Conn., assignor to Bevelacqua, Inc., New York, N. Y., a corporation of New York

Application March 3, 1949, Serial No. 1,194

Term of patent 3½ years

(Cl. D15—11)

To all whom it may concern:

Be it known that I, Salvatore Bevelacqua, a citizen of the United States, residing at Westport, Fairfield County, Connecticut, have invented a new, original, and ornamental Design for a Love Seat, of which the following is a specification, reference being had to the accompanying drawing, forming a part hereof.

Fig. 1 is a front elevational view of a love seat showing my new design;

Fig. 2 is a perspective view;

Fig. 3 is a side elevational view; and

Fig. 4 is a top plan view.

I claim:

The ornamental design for a love seat, as shown.

SALVATORE BEVELACQUA.
